PORTABLE RADIO CABINET

Samuel Frankel, 236 5th Ave., New York, N.Y.

Filed June 4, 1962, Ser. No. 70,401

Term of patent 14 years

(Cl. D56—4)

FIG.1

FIG.2

FIGURE 1 is a front perspective view of a portable radio cabinet embodying my new design; and

FIGURE 2 is a rear perspective view thereof.

The dominant features of my design reside in the portion shown in full lines.

I claim:

The ornamental design for a portable radio cabinet, as shown and described.
